(57) **CLAIM**

I claim the ornamental design for a holder, as shown and described.

DESCRIPTION

FIG. 1 is front/right/top perspective view of a holder; FIG. 2 is a rear/left/bottom perspective view thereof;

FIG. 3 is a top plan view thereof;

FIG. 4 is a bottom plan view thereof;

FIG. 5 is a front elevational view thereof;

FIG. 6 is a rear elevational view thereof; and,

FIG. 7 is a right side elevational view thereof.

The broken lines depict portions of the article that form no part of the claimed design.
